UNITED STATES PATENT OFFICE

WILLIAM E. WATKINS, OF NEW YORK, N. Y., ASSIGNOR TO COPPER PLATE SHEET AND TUBE COMPANY, OF NEW YORK, N. Y., A CORPORATION OF NEW JERSEY

ARCHING MECHANISM

Original application filed June 16, 1926, Serial No. 116,486. Divided and this application filed August 9, 1929. Serial No. 384,773.

This invention relates to mechanism for arching metal sheets, and is a division of my copending application, Serial No. 116,486, filed June 16, 1926.

5 In said application I have disclosed and claimed a process of treating metal sheets in which the sheets are fed continuously and successively through suitable apparatus by means of which they are first arched, then 10 pickled, then washed to remove the pickling solution, then flattened and dried, again arched, and then conveyed through an annealing furnace in arched form.

An object of the present invention is the 15 provision of improved means for arching metal sheets.

In the accompanying drawings,

Fig. 1 is a vertical, sectional view of the 20 arching mechanism;

Fig. 2 is a fragmentary elevation of part of the crowning mechanism shown in Fig. 1; and,

Fig. 3 is a fragmentary, transverse, sectional view taken on line 3—3 of Fig. 1 showing 25 details of the arching mechanism.

The arching mechanism comprises two co-operating sets of wheels or disks, one set being arranged above the other, and the two sets being adapted to force the center of each sheet 30 upward as it progresses, while holding the side edges of the sheet down.

In Fig. 1 I have illustrated a framework 101 having front upright portions 102 carrying an upper cross-beam 103. A screw-threaded adjusting rod 104 extends parallel to the beam 103 and is journaled at the ends of this beam. Two blocks 105 each have screw-threaded engagement with the adjusting rod 104. These blocks are each connected to an 40 upper supporting beam 106. The two supporting beams, each designated by the numeral 106, are supported at their rear ends by a second adjusting rod 107 extending parallel with a second cross-beam 108. Each of the 45 adjusting rods 104 and 107 is provided with right and left hand screw-threads so that when either of these rods is turned, as by applying a crank to a squared end such as that shown at 109a in Fig. 2, the adjacent 50 ends of the supporting beams 106 are brought

closer together or spread further apart, depending upon the direction of rotation of the adjusting rods.

Upper front bearing beams 109 are pivoted to each of the upper supporting beams 106, 55 as shown at 110. Each of the two beams 109 carries a plurality of stub shafts, each carrying a wheel or disk 111. These disks are inclined at an angle to the vertical, as shown in Figs. 2 and 3, and serve to engage the upper 60 surface of each of the sheets passed through the arching mechanism, so as to hold the edges of the sheets down while the center is being forced up by the lower set of arching disks 65 hereinafter described. The rear end of each of the upper bearing beams 109 is journaled in a bearing block 112, adjustably mounted on a corresponding supporting beam 106. The position of each bearing beam with respect to the corresponding supporting beam can be 70 varied by adjusting the screw 113 having a squared end 114 and a lock nut 115. It will be understood that a bearing block and an adjusting screw are provided for each of the bearing beams 109, as shown in Fig. 3. The 75 blocks 112 can be fixed to the supporting beams 106 in any adjusted position by tightening nuts 116 on bolts passing through slots 116a in the bearing blocks. This provides 80 independent adjustment of the rear ends of the two bearing beams 109.

A pair of upper rear bearing beams 117, each carrying four or five wheels or disks 111, is arranged with the forward end of each bearing beam journaled to the corresponding 85 bearing block 112, and with the rear end of each beam journaled to a rear bearing block 118. Each of the rear bearing blocks may be identical with the bearing blocks 112, and may be provided with the same adjusting and clamping devices. The rear bearing blocks 118 may be adjusted for the purpose of adjusting each of the rear bearing beams 117 independently of each other and of the front bearing beams 109. The disks 111 carried by the upper front and rear bearing beams are not power driven; they are simply rotatably mounted on stub shafts carried by the bearing beams.

The lower set of disks (shown at 126) 100

adapted to cooperate with the upper set of disks just described, comprises a plurality of wheels or disks of a diameter preferably larger than that of the disks 111 and each 5 mounted on a shaft extending at right angles to the direction of travel of the sheets through the arching mechanism. In Fig. 1, I have shown eight of these shafts, the forward six, designated by the numeral 119, being journaled in front bearing beams 120. Each of the two lower front bearing beams 120 is pivoted about the axis of the first shaft 119 and the rear end of each of these beams is detachably connected, as by means of a bolt 15 121 projecting through a slot in an integral extension 122 of the bearing beam, and secured to a lower supporting beam 123. An adjusting screw 124 can be used as a means for adjusting the position of the rear end of each lower bearing beam 120 with respect to the corresponding supporting beam 123. The two rear transverse shafts 119 are journaled in separate lower bearing beams 125, each having its forward end journaled on an 25 axis concentric with the axis of the last transverse shaft 119 carried by the front bearing beams 120. The rear end of each of the lower rear bearing beams 125 is detachably and adjustably connected to the lower supporting beam 123 in a manner similar to that of the rear end of each front bearing beam 120, thus permitting independent adjusting of each of the lower rear bearing beams.

The disks 126 carried by the shafts 119 are 35 somewhat larger than the disks 111 carried by the stub shafts on the upper bearing beams 109. Referring to Fig. 2, I have illustrated four disks 126 carried by the first shaft 119. These disks are arranged so that 40 the horizontal plane including the upper edges of the disks 126 coincides at least approximately with the horizontal plane including the lower edges of the upper disks 111. The first two or three shafts 119 may 45 each carry four disks 126 arranged substantially as shown in Fig. 2; the remaining shafts 119 preferably carry only two disks, as shown in Fig. 3. Where only two disks 50 are provided they are arranged closer together than the outside disks on the shafts carrying four disks apiece. All of the disks on the shafts 119 are preferably of the same diameter. The rear ends of each upper front bearing beam and the corresponding lower 55 front bearing beam are closer together than the front ends of these members, and accordingly the centers of the lower disks near the rear are closer to the centers of the upper disks 111. Accordingly, as the sheets pass 60 through the arching mechanism, the center of each sheet is forced upward, while the edges are held down, and in this way the sheets are delivered in arched form from the rear of the arching mechanism.

65 Each of the lower disks 126 is power

driven. The ends of the shafts 119 are provided with sprocket wheels 127 and adjacent sprocket wheels are connected by a sprocket chain passing over all of the sprocket wheels. The front sprocket 128 is driven by means of a chain 129 connected to a sprocket wheel on a counter shaft 131 driven from any suitable source. An adjustable idler sprocket wheel 135 is mounted on the lower supporting beam 123 and serves to take up the slack 75 in the sprocket chain passing over the sprocket wheels on the shafts 119.

I claim:

1. An arching mechanism for metal sheets comprising a plurality of shafts, a set of 80 lower rollers mounted on each of said shafts adjacent the center and adapted to engage the lower surface of the sheets, a plurality of sets of upper rollers rotatably supported above said shafts and adapted to engage the 85 upper surfaces of the sheets near each edge, the upper peripheral edge of said first set of lower rollers and the lower peripheral edge of the first set of upper rollers being arranged in substantially the same plane, the 90 distance between the centers of the rollers on each shaft and the adjacent upper rollers decreasing whereby the center of a sheet passed between said rollers will be forced upwardly and the edges held down. 95

2. An arching mechanism for metal sheets comprising a plurality of shafts, a set of lower rollers mounted on each of said shafts adjacent the center and adapted to engage the lower surface of the sheets, a plurality 100 of sets of upper rollers rotatably supported above said shafts and adapted to engage the upper surfaces of the sheets near each edge, the upper peripheral edge of said first set of lower rollers and the lower peripheral edge of the first set of upper rollers being arranged in substantially the same plane, the 105 distance between the centers of the rollers on each shaft and the adjacent upper rollers decreasing whereby the center of a sheet 110 passed between said rollers will be forced upwardly and the edges held down and means for driving said shafts.

3. Arching mechanism for metal sheets comprising a frame, a plurality of shafts 115 mounted in said frame, lower rollers carried by said shafts, bearing members pivotally mounted on said frame and adjustable with respect thereto, upper rollers carried by said bearing members and arranged 120 in sets, said lower rollers engaging the center of the under surface of said sheets and said upper rollers engaging the upper surfaces of said sheets near the edges thereof, the upper peripheral edge of the first set of lower rollers and the lower peripheral edge of the first set of upper rollers being arranged in substantially the same plane, the 125 distance between the centers of the upper and lower rollers decreasing whereby the 130

center of a sheet fed through said rollers will be forced upwardly and the edges held down.

4. Arching mechanism for metal sheets comprising a frame, a plurality of shafts mounted in said frame, lower rollers carried by said shafts, bearing members pivotally mounted on said frame and adjustable with respect thereto, upper rollers carried by said bearing members and arranged in sets, said lower rollers engaging the center of the under surface of said sheets and said upper rollers engaging the upper surfaces of said sheets near the edges thereof, the upper peripheral edge of the first set of lower rollers and the lower peripheral edge of the first set of upper rollers being arranged in substantially the same plane, the distance between the centers of the upper and lower rollers decreasing whereby the center of a sheet fed through said rollers will be forced upwardly and the edges held down, and means for driving said shafts.

5. Arching mechanism for metal sheets comprising a frame, a plurality of shafts mounted in said frame, lower rollers carried by said shafts, bearing members pivotally mounted on said frame and adjustable with respect thereto, inclined upper rollers carried by said bearing members and arranged in sets, said lower rollers engaging the center of the under surface of the sheets and said upper rollers engaging the upper surfaces of the sheets adjacent their edges, the upper peripheral edges of the first set of lower rollers and the lower peripheral edges of the first set of upper rollers being arranged in substantially the same plane, the distance between the centers of the upper and lower rollers decreasing whereby the center of a sheet passed between said rollers will be forced upwardly and the edges held down.

In testimony whereof I affix my signature.
45 WILLIAM E. WATKINS.
